UNITED STATES PATENT OFFICE.

CHARLES B. LIVERMORE, OF SEATTLE, WASHINGTON.

TICKET-HOLDER.

No. 870,445.

Specification of Letters Patent.

Patented Nov. 5, 1907.

Application filed June 7, 1907. Serial No. 377,820.

To all whom it may concern:

Be it known that I, CHARLES B. LIVERMORE, a citizen of the United States, residing at Seattle, in the county of King and State of Washington, have invented 5 certain new and useful Improvements in Ticket-Holders, of which the following is a specification.

This invention relates to improvements in ticket holders, of that class in which the ticket is inserted in the holder in a tight roll of the desired length, and fed 10 out in proper lengths by the partial rotation of the holder parts.

In my Patent Number 837,939, dated December 11th, 1906, I show a holder of the same character as the one about to be described and while the holder of the patent 15 serves its purpose well, and admirably accomplished the object of the invention, I deem the present holder an improvement, in that it is somewhat more simple and sightly, as well as being cheaper to manufacture, and less cumbersome than my former 20 device. Aside from these general differences suggested, I have changed the formation of the outer and inner tubes or sections, simplifying the outer tube, and forming the inner tube so that it will effectually grip the edge of the ticket to insure its being fed forward 25 to position to be torn off when the proper section or part of the holder is partially revolved.

The object of the invention is to provide a simple sightly, durable and handy holder, embodying such construction that its parts may be readily put together 30 and taken apart to facilitate the entry of the roll of tickets which are inserted in the inner tube or section of the holder, in a tight roll as shown in the drawings, and as will be described.

In the drawings; Figure 1 is a perspective view of 35 the holder, with the proper width of ticket extended, the view being enlarged for the sake of clearer illustration; Fig. 2 is a perspective view of the outer tube; Fig. 3 is a similar view of the inner tube; Fig. 4 is a central cross section taken through both tubes, with 40 ticket roll in place; Fig. 5 is a cross section taken through the inner tube near the closed end, without paper; Fig. 6 is a similar view of the inner tube taken near the open end; and Fig. 7 is a detail broken sectional view of the flange of the inner tube or section.

45 Referring to the drawings, the numeral 1 designates the outer tube, with one end open as indicated at 2 and the other closed by a flanged cap 3. For the full length of this tube, I provide a narrow slot 4. The material adjacent to one side of the slot is raised slightly to form 50 a lip 5 which extends slightly above the material adjacent to the opposite side of the slot. The end of the tube at the end of the lip 5 is contracted as indicated at 7 so that it forms a continuation of the circular open end of the tube, so as to adapt the end to fit properly 55 within the overhanging flange of the inner tube as will appear later on. I recess the open end of the outer tube

as shown at 8, which recess extends preferably for half the circumference of the tube and where it ends, the shoulders 9 are presented which co-act with a suitable stop on the inner tube. 60

The numeral 10 designates the inner tube having an open end 11 and whose opposite end is closed by a flanged cap 12, the flange being turned back and overhanging a portion of the tube. On this tube and within the flange I provide an abutment 11^a in the way of a short pin, which is adapted to travel within the recess 8 in the outer tube and at times engage the shoulders 9 upon said tube, so that the complete rotation of the tubes one upon the other is prevented. In the present instance the tubes are capable of making a half revolution. 70

The numeral 13 designates a longitudinal slot which is adapted to register with the slot 4 in the outer tube at times. The edges of this tube overlap, producing an under lip 14 and an over lip 15 and I preferably provide 75 two slits 16 in the over lip, thus forming a central section a, and two end sections b, which sections b lightly contact with the under lip, so that they will bear lightly on the ticket and hold the same after it has been torn off to insure the feeding of the appropriate length of ticket 80 when the tubes are manipulated to project the ticket to the position for tearing, while the central section a is preferably slightly above the under lip and not in contact therewith.

The numeral 17 designates a small bead which, when 85 the two tubes are assembled, is embraced by the overhanging flange of the outer tube. This bead serves to hold the two tubes together, that is to say, to prevent them from coming apart without design of the manipulator, while it is obvious that by merely depressing the 90 lip which carries the bead, said bead will be forced below the edge of the flange, when the two parts may be easily slid apart.

In operation, the ticket in a tight roll, is placed within the inner tube, with one end extending through the 95 slot 13, in the inner section, and the outer tube is telescoped upon the inner one with the ticket extending through the slot 4. That portion of the end of the outer tube which carries the bead is depressed, so that said bead will enter the groove within the flange when the 100 two parts will be held temporarily together. The tubes are assembled in such position that the abutment or pin 11^a will be within the recess 8. When the outer tube is held and the inner one revolved a half turn 105 be exposed in position to be torn off, and another ticket is in place to be forced out after the one just exposed has been torn off.

Claims

1. A ticket holder, comprising a casing formed of outer and inner tubular parts, the outer part being provided 110 with a longitudinal slot and two shoulders adjacent to its

open end, the inner of said parts being provided with a hollow head-like flange overhanging a portion of the inner part and provided within the flange with a pin or abutment which co-acts with the shoulders upon the outer part, said inner part being provided with a longitudinal slot adapted at times to register with the slot in the outer part.

2. A ticket holder comprising a casing formed of outer and inner tubular parts, each having a closed end, the outer of said parts being provided with a longitudinal slot, and a circumferential recess adjacent its open end, said recess terminating in shoulders, the inner of said parts being provided with a longitudinal slot and a head-like flange overhanging a portion of the inner part and adapted to receive and envelop the open end of the outer part, an abutment or pin within the flange of the inner part, co-acting with the shoulders for the purpose set forth, and a bead or projection carried by the outer part and adapted to be received within the flange of the inner part, whereby the parts are detachably united.

3. A ticket holder comprising a casing formed of outer and inner tubular parts each having a closed end, the

outer part being provided with a longitudinal slot and a circumferential recess terminating in shoulders, the inner part being provided with a longitudinal slot, and formed with an inner and outer lip adjacent to said slot, the ends of the outer lip being adapted to bear lightly upon the inner lip for the purpose set forth, and means for limiting the rotation of the parts one upon the other.

25

4. A ticket holder comprising a casing formed of outer and inner tubular parts, each provided with a longitudinal slot, the inner part being formed with an inner and outer lip, one overlapping the other adjacent to the slot in said part, the ends of the outer lip being so formed as to bear lightly upon the lower lip, while the central portion of said lip is out of engagement with said lower lip, and means for limiting the rotation of the parts one upon the other.

30

In testimony whereof I affix my signature in presence of two witnesses.

CHARLES B. LIVERMORE.
